FLUID-CONTROL DEVICE

Application filed December 19, 1921. Serial No. 523,288.

The invention relates to fluid control devices and is adapted particularly for use in controlling a portion of the exhaust gases of an internal combustion engine for heating the explosive mixture passing to the engine. The invention has for its main object the provision of a device by which the ratio between the amount of fluid passing through a main conduit and a by-pass may be automatically varied without the necessity of mechanical means, such as valves and the like.

Other objects of the invention reside in the novel features of construction and combinations and arrangements of parts as more fully hereinafter set forth.

In the drawings:

Figure 1 is a central section through a fluid control device embodying my invention;

Figure 2 is a sectional plan view of a modified construction on the line 2—2 of Figure 4;

Figures 3 and 4 are respectively cross sections on lines 3—3 and 4—4 of Figure 2.

As shown in Figure 1, the device comprises the inlet 1, the axially aligned main conduit 2 and the transverse bypass 3. To automatically control the fluid passing through the main conduit 2, the latter has a restricted entrance 4 with the annular inclined shoulder 5 connecting the inlet and main conduit, this shoulder being inclined in the direction of travel taken by the fluid. The bypass 3 connects into the inlet 1 at a point in advance of this annular shoulder. In the operation of the apparatus above described it is found that as the velocity of the fluid through the inlet 1 is increased a larger proportion of the fluid passes through the by-pass than it does at lower velocities and this may be explained by the fact that the fluid strikes and is deflected by the annular inclined shoulder 5, thereby forming eddies which automatically retard the passage of the fluid through the main conduit. At the higher velocities the resistance due to the eddies formed by the shoulder is more pronounced than at the lower velocities so that the ratio between the amount of flow through the main conduit and by-pass does not remain constant, but varies with different velocities.

In the case of liquids, the main and by-pass conduits are preferably horizontal, whereas in the case of gases, the position of the device is immaterial.

As shown in the modified construction of Figures 2, 3 and 4, the fluid control device is used for automatically controlling the amount of exhaust gases passing into a chamber surrounding a portion of an induction conduit leading to an internal combustion engine. In detail, 6 is a chamber surrounding the passageway 7 adapted for the passage of explosive mixture leading to an internal combustion engine. 9 is an inlet adapted for the passage of exhaust gases from the engine which communicates with the chamber 6 by means of a restricted passageway 8, the restriction being formed by the annular inclined shoulders 11. 12 is an outlet from the heating chamber 6 and together with the passageway 8 and the chamber 6 forms a main conduit for the exhaust gases. Connected into the inlet 9 at a point in advance of the annular shoulders 11 is a by-pass 10 which leads around the heating chamber and preferably connects into the heating chamber outlet 12. For controlling the amount of exhaust gases passing through the device, there is the valve 13 to the rear of the point of communication of the heating chamber outlet and the bypass outlet, this valve being actuated by suitable means, as for example, the lever 14 connected to the shaft 15 upon which the valve is mounted.

With this arrangement, the action of the exhaust gases is substantially the same as that of the fluid in the device shown in Figure 1. When the exhaust gases are passing through the inlet 9 at a low velocity or rate of flow as when the engine is idling, they will pass through the main conduit 12, by way of the restricted passageway 8 and the heating chamber 6. However, as the velocity of these exhaust gases increases beyond a certain point, resistance to their passing through the passageway 8 is increased and they seek the path of travel of the least resistance, which is through the bypass, so that the heat conducted to the explosive mixture passing through the passageway 7 is not allowed to become too high.

In other words, means is provided for automatically regulating the heating of the explosive mixture without the necessity of valves or the like. Thus it is seen that the amount of exhaust gases entering the heating chamber depends upon the velocity of the exhaust gases entering the inlet which in turn depends upon the amount of explosive mixture passing through the passageway of the device to the engine.

From the above description it will be readily seen that I have provided a device having an inlet, a main conduit and a bypass so constructed that the flow of the fluid passing through the main conduit is automatically controlled. Furthermore, it will be seen that I have more particularly brought out a heating fluid control device which automatically controls the amount of heating fluid used for heating the explosive mixture passing to an internal combustion engine, this heating fluid depending upon the amount of explosive mixture passing to the engine and upon the speed of the engine.

25 What I claim as my invention is:

1. In a fuel vaporizer the combination of a body having a fuel passageway therethrough, a chamber surrounding said passageway and adapted for the passage of a heating fluid, said chamber having a restricted inlet, and a bypass passageway connecting into said inlet forward of its restriction.

2. A fuel vaporizer comprising a body having a fuel passageway therethrough and an exhaust passageway surrounding said fuel passageway, a conduit communicating with said exhaust passageway provided with a restriction at the entrance thereto, a second conduit communicating with the opposite side of said exhaust passageway, and a bypass connecting said first mentioned conduit in advance of said restriction to said second mentioned conduit.

3. In a fuel vaporizer, the combination of a body having a fuel passageway therethrough, a main heating passageway in heat conducting relationship therewith, an inlet conduit for heating fluid connected to said heating passageway and provided with means forming an abrupt contraction in section, an outlet conduit connected to said heating passageway, and a bypass not in heat conducting relation with said fuel passageway, said bypass being connected into said inlet conduit in advance of said contracted section and also connected to said outlet conduit.

4. In a fuel vaporizer, the combination with a fuel passageway, of a main heating passageway in heat conducting relationship therewith, a bypass not in heat conducting relationship with said fuel passageway, an inlet conduit connected to both said main passageway and said bypass, and means fixedly arranged in said inlet conduit between said main passageway and said bypass for

automatically increasing the proportion of heating fluid passing through said by-pass as the velocity through said inlet conduit increases.

In testimony whereof I affix my signature. 70
ANTOINE P. PLAUT.
